SNAP ACTING THERMAL SWITCH

Edward Bletz, Lexington, Ohio, assignor to Westinghouse Electric & Manufacturing Company, East Pittsburgh, Pa., a corporation of Pennsylvania

Application August 27, 1938, Serial No. 227,043

5 Claims. (CL 297—15)

My invention relates to thermostatic devices, and more particularly to a furcated, bimetallic snap-acting thermal switch.

An object of my invention is to provide a bimetallic element for a snap-acting thermal switch element that may be manufactured by a simple stamping operation without the necessity of preshaping such element.

A further object of my invention is to provide a simple thermostatic element for a snap-acting thermal switch and to provide means for attaching it to a base so as to make the element snap-acting in action.

Another object of my invention is to provide adjustable means for changing the curvature of the thermostatic element to afford means for adjusting the differential of operation of the thermostatic switch.

A further object of my invention is to provide a rugged, efficient, inexpensive, snap-acting switch which may or may not be adjustably operated after being assembled.

A still further object of my invention is to provide adjustable means for changing the curvature of the thermostatic element after being assembled.

Other objects of my invention will either be pointed out specifically in the course of the following description of a device embodying my invention, or will be apparent from such description.

In the accompanying drawings,

Figures 1 and 2 are, respectively, side elevational views, partly in section, of a device embodying my invention in each of its two operating positions.

Fig. 3 is a sectional view taken along the line III—III of Fig. 1.

Figs. 4 and 5 are a top plan view and a side elevational view, respectively, of the operating element and mounting device therefor.

Fig. 6 is a top plan view of the bimetallic operating element including in the structure shown in Figs. 5 and 6.

Figs. 7 and 8 are plan and side elevational views, respectively, of a member included in the mounting device shown in Figs. 4 and 5.

Figs. 9 and 10 are plan and side elevational views, respectively, of an additional member shown in Figs. 5 and 6.

Fig. 11 is a perspective view of a modified form of the operating element shown in Fig. 6.

Fig. 12 is a top plan view of a modified form of the structure shown in Fig. 4, illustrating

means for changing the curvature of the thermostatic element, and

Fig. 13 is a sectional view taken along the line XIV—XIV in Fig. 12.

Referring to the accompanying drawings, I show a snap-acting, furcated, bimetallic thermal switch 10 comprising a multi-furcated bimetallic operating element 12, an element support or mounting device 14 therefor, a main supporting structure or base 15, and a plurality of cooperating contacts 17 and 19 operatively associated with the bimetallic element 12 and base 15, respectively.

The element support or mounting device 14 includes a top member 16, a base member 18 and a plurality of pins or studs 20 which cooperate with the top and base members and the bimetallic element 12.

The multi-furcated bimetallic operating element 12 is preferably formed or constructed from a single sheet of bimetallic material. However, it is to be understood that the element may be constructed in any other desirable manner. The element 12 comprises a plurality of exterior furcations 22 and at least one interior furcation 24, and an end portion 26. The furcations 22 and 24 are preferably formed integral with the end portion 26 of the member 12. However, they may be rigidly attached thereto in any other desired manner. The furcations 22 and 24 are substantially the same length and have slots or apertures 28 located therebetween. Small circular apertures 30 are positioned within the free ends of the exterior furcations 22 and a similar aperture 32 is positioned within the free end of the interior furcation 24 somewhat closer to the end thereof than the apertures 30 position within the furcations 22, substantially as shown in Fig. 6. The apertures 30 and 32 cooperate with the element support or mounting device 14, which is adapted to maintain the interior furcation 24 in a curvature substantially opposite to that of the exterior furcations 22, substantially as hereinafter described.

The bimetallic element 12 is rigidly attached, at one end thereof, to the element support 14, as hereinabove described, and has attached at its free end the movable contact 17, which, in this instance, comprises an elongated bar 33 loosely attached to the element 12 by the ball-headed rivet 35, as shown in Figs. 1, 2 and 3. The rivet 35 and bar 33 are insulated from element 12 by a suitable insulating grommet 37. However, it is to be understood the movable contact 17 may be constructed and insulatedly at-

tached to the element 12 in any desired manner.

The element support or mounting device 14 is, in this instance, formed from two main structural members; namely, a top member 16 and a bottom member 18. The top member 16 is substantially a flat metallic bar which has rigidly attached thereto a plurality of pins or studs 20 positioned in substantially a straight line. These pins cooperate with and retain the operating element in a predescribed curvature, substantially as hereinafter described.

The base 18 includes a main portion 34 and an upwardly extending portion 36, located at the rear end thereof. The upwardly extending portion 36 extends above the main portion 34 an amount substantially equal to the thickness of the multi-furcated bimetallic element 12. A plurality of apertures 38 are positioned within the main portion 34 to cooperate with the pins 20 in a manner substantially as hereinafter described. The support is then formed by having the top plate 16 positioned upon the upwardly extending portion 36 of the base 18 and rigidly attached thereto by means of suitable temporary assembly screws 40a.

The main supporting structure or base 15, shown in Figs. 1 and 2, comprises, in this instance, an elongated main-body portion 21 having a depending mounting portion 23 at one end thereof. However, it is to be understood that the supporting structure 15 may be formed in any other desired manner.

An adjusting device 31, including a set-screw 25, is threadedly attached to the base 15, intermediate the ends thereof, by any suitable bushing 27. The set-screw 25 has a reduced-diameter portion 29 located at the lower end thereof which cooperates with the central leg of the bimetallic element 12. This reduced-diameter portion 29 cooperates with the element 12 in such a manner that as the set-screw 25 is rotated there will be no binding action between the portion 29 and the element 12. In addition, the portion 29 fits the central leg of the element 12 so as to substantially prohibit any movement therebetween along the axis of set screw 25 as the element 12 flexes from one position to another. The adjusting screw 25 is then free to regulate the operation of the element 12 and thermostat 10.

The stationary contacts 19 are insulatedly connected to the free end of base 15, and comprise, in this instance, a contact portion 39 and a terminal portion 41, which are, in this instance, threadedly engaged so as to be rigidly attached to the base 15. Insulating grommets 43 are operatively associated with the contacts 19 to insulate them from the base 15. However, it is to be understood that the contacts may be formed and mounted upon the base 15 in any desired manner so that they cooperate with the movable contact 17.

In assembling the operating element 12 and mounting device 14, the multi-furcated bimetallic operating element 12 is positioned upon the base 16 of the support or mounting device 14 and the top member 16 is positioned thereon. The pins or studs 20 operatively associated with the top member 16 then cooperates with the apertures 30 and 32 located within the free ends of the furcations 22 and 24, respectively, substantially as hereinafter described, and, in addition, with the apertures 38 located in the base 18. The top member 16 is then rigidly attached to the base 18 by means of the temporary assembling screws 40a or in any other suitable manner.

When it is desired to mount the assembled operating element 12 and mounting device 14 upon the base 15, the device 14 may be rigidly attached to the depending portion 23 of such base. The temporary assembling screws 40a may be removed from the device 14 and replaced by screws 40 which will cooperate with the base 15 and rigidly attach the device thereto. However, it is to be understood that the mounting device 14 and bimetallic operating element 12 may be attached to base 15 in any other suitable manner.

Inasmuch as the pins 20, operatively associated with mounting device 14, are located in substantially a straight line, and inasmuch as the apertures 30 and 32, positioned within the free ends of the furcations 22 and 24, are not located in a straight line, when the pins 20 are inserted through the apertures 30 and 32, the free end of the intermediate furcation 24 will be forced inwardly causing such furcation to be curved with respect to the exterior furcations, say, upwardly, substantially as shown in Fig. 5. In addition, inasmuch as the intermediate furcation 24 is substantially the same length as the exterior furcations 22, it follows that, when taking the device as a unit, as the free end of the intermediate furcation 24 is biased inwardly, due to the irregular position of aperture 32, located in the free end thereof, such furcation becomes in effect, between the points of support, longer than the exterior furcations. In other words, assuming that the end portion 26 and exterior furcations 22 of member 12 comprise a frame for the thermostat which is attached to the supporting structure 14, the intermediate furcation 24 may then be construed as being a bridging member which is longer than its supporting frame.

It is to be understood that, if desired, the apertures 30 and 32 may be located in a straight line and the pins 20 positioned in an irregular line, with the intermediate pin 20 located closer to the edge. Accordingly, when the intermediate pin 20 cooperates with aperture 32, the intermediate furcation 24 may likewise be curved relatively upwardly substantially as hereinabove described.

The relative upward curvature of the intermediate furcation 24, together with its effective length being greater than that of the main element 12, causes the element 12 to have a similar curvature. However, it is apparent that such curvature thereof will be less than that of the intermediate furcation 24, as shown in Fig. 2.

During operation, as the thermostat and the bimetallic operating element 12 are subjected to an increase in temperature, the internal stresses of the element 12 are changed. Inasmuch as such member is formed of bimetallic material, it will tend to change its curvature or straighten itself and then reverse its curvature. By reason of the fact that the intermediate furcation is effectively longer than the frame of member 12, the movement or reversal of curvature of such element results in a reversal of curvature of the intermediate furcation 24 and the entire operating element 12 with an abrupt or snap-action. The movable contact 17 positioned upon the free end of element 12 is disengaged from the stationary contacts 19 by such snap-action, as shown in Fig. 2.

Upon cooling the element 12, it again tends to straighten itself, causing the intermediate furcation 24 and the exterior furcations 22 to return to their original position with a snap-action. The contact 17 will then be reengaged with the sta-

tionary contacts 19 with a snap-action, as shown in Fig. 1.

As the element 12 changes from one position to another, the intermediate furcation 24 figuratively passes through the element 12 from one side to the other. This action tends to cause a longitudinal stretching of the exterior furcations 22. The more readily these furcations stretch in response to temperature and then return to their original position, the more readily will the intermediate furcation change its position. Accordingly, it will be understood that the readiness with which such intermediate furcation 24 reverses its curvature determines the range of operation of the thermostat. That is, the more readily it operates, the smaller will be its range of operation.

It, therefore, follows that, if desired, the exterior furcations of the bimetallic element 12 may be formed in a sinusoidal or wavy manner substantially as shown by 22a of element 12a in Fig. 11. The wavy curvature of the exterior furcations 22a then permits such furcations to readily expand and contract longitudinally as the elements 12 flexes from one position to another, and, in turn, permits the thermostat to operate on a very small range or differential between its "off" and "on" positions.

As an important modified form of the mounting structure or device 14 shown in Figs. 4 and 5, the upwardly extending portion 36a of base 14a has a threaded aperture 48 located substantially at the midpoint thereof intermediate the screws 40a, as shown in Figs. 12 and 13. An adjusting screw 42 may then be threadedly engaged with the aperture 48 so as to effect longitudinal engagement with the free end of the intermediate furcation 24a. The screw 42 may then be run in or out of or manually adjusted with respect to the base 14a so as to change the relative position of the free end of the intermediate furcation 24a, and to effect changes in the curvature thereof. When using such a structure, the aperture 32a, located in the free end of the furcation 24a, is slotted so as to permit free movement of the free end of the furcation 24a in response to the movement of the screw 42 (Fig. 13).

As the adjusting screw 42 is moved with respect to the base, the furcation 24a assumes corresponding changes in curvature; which, in turn, permits the thermostat to be readily adjusted to the desired operating differential after having been assembled. This feature is extremely important inasmuch as it permits the thermostat to be assembled and adjusted without the use of many expensive previously used tools and jigs.

Various other modifications may be made in the device embodying my invention without departing from the spirit and scope thereof, and I desire, therefore, that only such limitations shall be placed thereon as are imposed by the prior art and the appended claims.

I claim as my invention:

1. In a circuit-controlling device, a member having a plurality of furcations of substantially equal length, a supporting structure therefor, and means comprising said structure for cooperatively supporting the free ends of said furcations, said furcations having lines of contact near one end with said structure and being retained in unaligned formation by said structure to cause one of said furcations to become in effect longer than the others and to assume a curvature greater than that of the remaining furcations, projec-

tions of said furcations between said respective lines of contact and the other ends of the respective furcations on a plane parallel to the plane of an outer furcation being substantially equal.

2. In a circuit-controlling device, a multi-furcated bimetallic member, the furcations being of substantially equal length and the free end of one of them having an aperture initially unaligned with apertures in the others, a supporting structure therefor, a plurality of substantially aligned fastening means operatively associated with the structure, and means comprising said structure and fastening means for cooperatively supporting the free ends of said furcations, said furcations having lines of contact near one end with said support and being retained with said apertures in substantial alignment thereby to bow said one furcation relative to said others, projections of said furcations between said respective lines of contact and the other ends of the respective furcations on a plane parallel to the plane of an outer furcation being substantially equal.

3. In a circuit-controlling device, a multi-furcated bimetallic member, the furcations being of substantially equal length and the free end of a central one of them having an aperture initially unaligned with apertures in the others, a supporting structure operatively associated with the free ends of the furcations including a base, a cover plate and a plurality of studs associated therewith, said structure cooperatively supporting the free ends of the furcations, said furcations having lines of contact near one end with said support and being retained with said apertures in substantial alignment thereby to bow said one furcation relative to said others, projections of said furcations between said respective lines of contact and the other ends of the respective furcations on a plane parallel to the plane of an outer furcation being substantially equal.

4. In a circuit maker and breaker, a multi-furcated bimetallic member, said member having at least one interior furcation, a supporting structure including a base, fastening means rigidly securing one end of the outer furcations and adjustably securing one end of said interior furcation to said base, said furcations having lines of contact near one end with said supporting structure, and adjusting means supported by the base and operatively associated with the adjustably secured end of the interior furcation to vary the curvature of such furcation, projections of said furcations between said respective lines of contact and the other ends of the respective furcations on a plane parallel to the plane of an outer furcation being substantially equal.

5. In a circuit maker and breaker, a multi-furcated bimetallic member, said member having at least one interior furcation, a supporting structure including a base, fastening means rigidly securing one end of the outer furcations and adjustably securing one end of said interior furcation to said base, said furcations having lines of contact with said base, and an adjusting screw threadedly engaging the base and operative longitudinally against the adjustably secured end of the interior furcation to increase or decrease the curvature of such furcation, projections of said furcations between said respective lines of contact and the other ends of the respective furcations on a plane parallel to the plane of an outer furcation being substantially equal.
